COIN-CONTROLLED VENDING-MACHINE.

1,348,876.

Specification of Letters Patent. Patented Aug. 10, 1920.

Application filed June 22, 1916. Serial No. 105,274.

To all whom it may concern:

Be it known that we, CLARENCE W. HOBBS and EUGENE A. COPELAND, both of Worcester, in the county of Worcester and State of

5 Massachusetts, both citizens of the United States, have invented a new and useful Improvement in Coin-Controlled Vending-Machines, of which the following is a full, clear, and exact description, reference being had to

10 the accompanying drawings, forming a part of this specification, in explaining its nature.

The present invention relates to an improvement in coin or check controlled vending machines and essentially to a power-operated machine.

15 Among the objects of the invention is to provide a machine of the above character, simple in construction, quick, positive and accurate in operation, and responsive only to 20 legal coins of proper denomination.

The invention can best be seen and understood by a detailed description in the light of the drawings and in which—

Figure 1 is a front elevation of the machine.

Fig. 2 is a side elevation of the lower working portion of the machine.

Fig. 3 is a plan of a portion of the working parts of the machine.

30 Fig. 4 is a section on the line 4—4 of Fig. 1.

Figs. 5 and 6 are side elevations of certain elements of the machine to which special reference will later be made.

Fig. 7 is a section on the line 7—7 of Fig. 1.

35 Fig. 8 is a section on the line 8—8 of Fig. 1.

Referring to the drawings:

1 represents the frame of the machine. Arranged at the top of the fore part of the frame is a coin gage 2 having in it the customary slot through which the coin, if of proper general form, is first inserted.

3 represents a coin-testing device which is arranged back of the coin gage and into which the coin passes after passing the gage.

40 45 This device forms the subject-matter of an application for Letters Patent of the United States filed of even date herewith and to which reference is hereby made for a fur-

ther description of its construction and operation. In general the operation of the 50 device is to measure coins for diametrical size, and other details referred to in said application. If the requirements of the device are not satisfied the coin will be ejected by the device and fall into a hopper 4 and 55 thence to a chute 5 connected with a rejected-coin pocket 6 arranged on the outside of the casing (not shown), which incloses the entire machine, and where it may be recovered by the one inserting the coin. If the requirements of the testing device 4 are satisfied the coin will descend through it and pass into and through a downwardly-inclined chute or lead 7.

The machine is started by the coin during 60 its descent through the chute 7, this being initially accomplished by the engagement of the coin with a trip lever 8 which controls, and as a part of such control, effects the release of a drop lever hammer 9 the fall of 70 which starts the machine, as will later be explained.

The trip lever 8 is arranged adjacent the lower end of the chute 7. The lever comprises a butt or thickened portion 10 from 75 the forward end of which extends a wire 11 having a bent end 12. The butt of the lever is secured by a pivotal connection 13 to turn upon a supporting bracket 14 fixed to the frame of the machine. That portion of the 80 butt 10 which extends back of the pivotal connection presents an end surface or edge 15 and a top surface 16; it has also attached to it a downwardly and backwardly inclined spur or finger 17. The bent end 12 of the 85 lever is contained within a slot 18 cut within the side, and preferably both sides of the chute 7, the end 12 contained within the slot extending transversely through the hollow of the chute. The slot 18 is cut upon an arc 90 concentric with the path described by the turned end 12 of the lever when the lever is rocked. The relative disposition of the lever and slot in relation to the way through the chute or path traversed by the coin in 95 passing through the chute is such that, when

the forward end of the lever is turned upwardly, which defines its operative position, the bent end thereof then contained in the top end of the slot will lie directly in the 5 path of the descending coin so that the lever will be rocked by it until the lever has been turned to a position where the bent end thereof will have reached substantially the bottom of the slot, when the coin, having 10 accomplished the purpose of rocking the lever, continues its course through the chute.

Arranged back of the trip lever 8 is an angular bent lever or dog 20 pivotally secured to the frame of the machine. This 15 lever or dog has arms 21 and 22, respectively, of which the arm 21 is an overweighted arm and has secured to the side thereof a pin 23. The arm 22 of the lever extends upwardly over the top rear end surface 16 of the trip 20 lever and is provided with a yielding contact 24 which engages this surface as the dog is turned.

The drop lever hammer 9 is arranged adjacent and below the rear end of the trip 25 lever and is pivoted by a connection 26 to a bracket 27 fixed to the frame of the machine. This lever comprises simply a heavy bar controlled to assume a slightly inclined vertical inoperative position and gravitating 30 therefrom when released to a substantially horizontal working position, the descent of the bar being arrested by a yielding stop 28 on the frame of the machine. The relative arrangement of the parts is such that when 35 occupying its substantially vertical inoperative position the forward or free end of the hammer has bearing against the rear end 15 of the trip lever, this lever then occupying its operative position as outlined above.

40 The overweighted arm 21 of the dog will then be slightly displaced and have bearing against the end of the hammer. When the trip lever is rocked by the coin on its descent through the chute the rear end of the lever 45 will become raised, releasing the hammer which then falls by gravity. Simultaneously with the fall of the hammer the arm 21 of the dog will move forward seeking its center of gravity, and the pin 23 carried by 50 it will be moved to occupy a position beneath the spur or finger 17 on the end of the trip lever and act to hold down the trip lever in that position to which it has been rocked by the coin with the bent end 12 of 55 the lever occupying a position at the bottom of the slot in the chute. These positions of the trip lever and its controlling dog are maintained until the return of the hammer. As the hammer is raised the end thereof 60 will pass beneath the under side of the rear end of the trip lever and engage the arm 21 of the dog, moving this arm backward and the pin 23 carried by it from beneath the spur 17 and at the same time so rocking the 65 dog that the arm 22 thereof or contact 24

carried by it will be brought into engagement with the top surface 16 at the rear end of the trip lever, rocking it and restoring it to its initial raised or operative position, all the parts then being in position to again operate as above described. 70

The energy developed by the fall of the hammer starts the machine. The motive power employed is an electric motor 35 through which a current is passed from any 75 convenient source of supply by leading-in-and-out wires 36 and 37, respectively (see Fig. 3). The wire 36 is provided with a switch by which the circuit is made or broken, the switch comprising a contact 80 member 38 which is moved into and out of engagement with separate contacts 39 and 40, respectively, in the leading-in wire. The contacts 39 and 40 are each carried by a supporting arm 41. Both arms are secured 85 to an insulated block 42 which in turn is secured by an arm 43 to the bed 45 of the machine, which bed supports also many of the operating parts of the machine later to be referred to. 90

The contact member 38 is carried by a threaded pin 47 which extends through a hub 48 on the upper end of a lever 49. The pin and contact member carried by it are adjustably secured by nuts 50 arranged upon 95 the pin and bearing, respectively, against the ends of the hub. The lever 49 is pivotally secured by a pin 51 to a fixture 52 on the bed 45 of the machine. The lever has a boss 53 projecting laterally from the side 100 thereof and carries also a cam roll 54. Beyond the point of its pivotal connection the lever is extended by an arm 55 against which bears a spring-pressed piston or plunger 56. This piston is contained within a casing or 105 housing 57 arranged on the bed of the machine. The piston has extending from the rear side thereof a stem 58, which extends through the rear end of the housing and is held by a pin 59 which extends through the 110 end of the stem and bears against the outer end of the housing. Arranged upon the stem within the housing is a spring 60 which bears against the inner end of the piston and also against the inner end of the housing. 115 The tensional bearing of the spring against the plunger forces it outward to have a constant tensional bearing against the arm 55 of the cam lever 49, which tends to throw the working arm of the lever forward and the 120 contact member 38 carried by the lever into a disengaging position thereby leaving the circuit controlling the motor normally open. 125

62, 63 are a brace of levers. These levers at the bottom ends thereof are secured to a common connecting hub 64 which is pivotally secured by a pin 65 to brackets 66 on the bed 45 of the machine. At the top ends the levers are connected by a common cross-head 67. The lever 63 beyond the cross- 130

head is provided with a curved extension 69 carrying a cam wheel 70. The cross-head 67 of the respective levers presents on the top side thereof a plane surface 72 and also 5 an incision forming a shoulder 73. With this plane surface and shoulder of the cross-head there co-operates a releasable latch 74, later to be referred to, which assists in controlling the brace of levers.

10 Arranged back of the cross-head 67 is a spring-pressed plunger 76 contained within a casing or housing 77 on the bed of the machine. This plunger is provided with a stem 78 which extends through the rear end 15 of the casing 77, thence loosely through the cross-head 67. The end of this stem is threaded and arranged thereon is a nut 79 adjusted to have bearing against the outer side of the cross-head and secured in place 20 by a cotter pin 80 passed through the end of the stem. Arranged upon the stem 78 within the casing is a coiled spring 82. Accordinging to the arrangement and operation of the parts the plunger is drawn back into the 25 casing contracting the spring 82, which accordingly bears with compression against the plunger to make the same active. The drawing back of the plunger for compressing the spring is obtained, as will later be 30 more fully explained, by the moving outward of the cross-head 67, the cross-head then bearing against the nut 79 which through the stem 78 withdraws the piston or plunger to compress the spring.

35 Bearing against the outer end of the plunger, outside the casing in which it is contained, is a boss 83 on the side of a lever 84. This lever is pivotally secured to a fixture 85 on the bed of the machine, the pivotal 40 connection being secured by the pin 51, which is the same pin that forms the pivotal connection for the lever 49 above referred to. Beyond the point of its pivotal connection the lever 84 is extended by an 45 arm 86 against which bears a spring-pressed piston or plunger 87. The tensional bearing of this piston operates to hold the lever 84 in a normal retracted position with bearing against the end of the plunger. The yielding 50 retention of the lever 84 is such, however, that it may be moved forward by the plunger as the plunger is moved forward by the action of the spring 82 backing it. The lever 84 is positioned to engage the boss 55 83 on the lever 49 as the lever 84 is moved forward by the plunger 76. The top 88 of the lever 84 provides also a stop to which special reference will later be made.

From the above description it will be seen 60 that both the cam lever 49 and the lever 84 are impelled to normally maintain a retracted position. Assuming that both of these levers are in their retracted positions with the plunger 76 also retracted and the spring 65 82 compressed, the following action will

take place in the event that the plunger is suddenly released: The plunger will first engage the lever 84 and throw this lever forward. As the lever 84 is thrown forward by the plunger it will carry the lever 49 with it 70 through the engagement of the lateral offset 88 on the lever 84 with the boss 53 on the lever 49. The throwing forward of the lever 49 throws the contact member 38 carried by this lever into engagement with the contacts 75 39 and 40 of the leading-in wire and accordingly closes the circuit. The proper positioning of the contact member between the contacts 39 and 40 is defined by the engagement of the lever 49 with a yielding stop 80 arm 90 suitably fixed to the bed or frame of the machine. As the plunger is moved back or retracted compressing the spring 82 the lever 84 will follow it back maintaining its contact therewith. The lever 49 would also 85 be retracted, breaking the circuit, unless this lever was otherwise prevented from retraction, as is the case, as will later be explained, it being especially to be noted that both the plunger 76 and the lever 84 may be retract- 90 ed without retraction of the lever 49 owing to the separation and independent action of the levers 49 and 84.

The plunger 76 is retracted and set, compressing the spring 82 and permitting the 95 normal retraction of the levers 84 and 49 by the moving outward or pivotal retraction of the levers 62 and 63 and cross-head 67 carried by these levers, the cross-head, as the levers are retracted, engaging the nut 79 and 100 accordingly through the stem 78 drawing back the plunger.

When this takes place the spring 82 will of course exert considerable drawing tension upon the cross-head, which is maintained in 105 its retracted position against the tension of the spring by means of the releasable latch 74 before referred to. This latch consists of a lever pivotally secured to the bed of the machine behind the cross-head by a pin 92, and 110 comprises arms 93 and 94 and also a projecting wing or finger 95. The arm 93 is a latching member or that which makes a latching engagement with the cross-head 67, this arm being yieldingly maintained to bear 115 against the top side of the cross-head by means of a spring-pressed finger 96 bearing against the arm 94 of the device. As the cross-head is moved back into its retracted position the latch member or arm 93 will 120 slip over the top surface of the cross-head and into the incision formed therein and bear against the shoulder 73, maintaining the cross-head accordingly in its retracted position against the tension of the spring 82 125 when the pressure tending to retract the cross-head has been relieved.

When the latch is released from the cross-head the plunger will then be thrown forward by the spring 82, closing the circuit 130

for energizing the motor and starting the machine as above described. The release of the latch from the cross-head is effected upon the drop of the hammer 9 by a lever 97 fixed 5 to a spindle 98 which turns in a bearing 99 on the bed of the machine. One arm of the lever 97 bears a wheel 100 adapted to engage the finger 95 of the latching device, turning the same and raising the latch arm 93 for 10 releasing the cross-head as the lever 97 is turned. The lever 97 is turned by the hammer 9 on the drop thereof by means of a connecting link 101 pivotally secured at one end to the lever 97 and at the other end to 15 the drop hammer. Attention is also directed to the arm 102 secured to the spindle 98 and cam wheel 103 carried by the arm.

After the closing of the circuit the motor operates to turn a main shaft 105 which 20 turns within boxes 106, 107, respectively, mounted on the bed of the machine. Motion is applied to the shaft 105 from the motor through a motor shaft 108, worm 109, worm gear 110, friction members 111 and friction 25 plates 112 and 113, respectively. The worm 109 is driven directly by the motor shaft. The worm gear 110, immediately driven by the worm, is loose upon the main shaft 105. The friction washers 111 are disposed between 30 the friction plates 112 and 113 and the sides of the worm gear. Both friction plates 112, 113, are keyed to the main shaft to rotate therewith, but are movable longitudinally thereon. The hub of the friction plate 112 35 has bearing against the side of the fixed box 106 supporting the main shaft. Arranged upon the main shaft and bearing against the outer end of the friction plate 113 is a coiled spring 114 held under tension by means of 40 a nut 115 on the end of the shaft. The arrangement of the parts is such that the main shaft will be driven from the motor only through frictional contact between the friction plates, interposed washers and sides of 45 the worm gear. A frictional connection is thus resorted to in order that the motor may rotate independently of the main shaft in case the rotation of the main shaft should become suddenly stopped, or to compensate 50 for any momentum of the motor after the stopping of the main shaft during the ordinary operation of the machine.

The main shaft 105 carries a series of cams 118, 119, 120 and 121, respectively, all 55 of which are suitably fixed to the shaft and rotated thereby. Of these cams the cam 118 is a timing cam which by its engagement with the top 88 of the lever 84, acting as a stop, permits only a single complete revolution 60 of the main shaft during the operation of the machine after the insertion of the coin.

The cam 119 is a reset cam, operating, as will presently be more fully explained, soon 65 after the starting of the main shaft to en-

gage the cam wheel 70 and throw back the cross-head 67 until it is automatically engaged and held in an operative position by the latch 74. The reset cam 119 acts at the same time to engage the cam roll 103 and thereby through the arms 102 and spindle 98 turns the lever 97, and this in turn through the link 101 raises the drop hammer 9, resetting it, and also the trip lever 8. 70

Cam 120 is a contact-controlling cam operating by engagement with cam roll 54 on lever 49 to hold the contact member 38 in place between the contacts of the leading-in wire and thereby to maintain the circuit closed during and after the resetting of the 80 trip mechanism and parts acting with it, the lever 84, which initially assisted in closing the circuit, being then allowed to return to its original position, when its top 88 may be engaged by the timing cam 118 at the end 85 of the shaft's cycle of rotation.

The cam 120 acts also to release the lever 49 to assume its normal position, separating the contacts and breaking the circuit at the end of the cycle of movement of the main 90 shaft.

The cam 121 is one controlling a coin detector 125. As has been previously described, the coin after rocking the trip lever 8 for releasing the hammer and starting the 95 machine, continues its course through the chute 7. From the chute it enters the coin detector, which is a detector for detecting standard coins of proper denomination like that shown and described in Letters Patent 100 of the United States No. 1,042,968, of October 29, 1912, and to which reference is hereby made for a further description of its construction and operation. The only elements necessary to be referred to in the present connection are the operating handle 126 or the detector and also the movable valve 127, which handle and valve correspond, respectively, with the operating handle and valve shown in said patent. 105 Connecting with the operating handle 126 is a link 128 which has pivotal connection with the cam lever 129 pivotally secured to the bed of the machine at point 130 and bearing a cam roll 131 adapted to be engaged by the cam 121, before referred to. Engaging the lever 129 is a spring-pressed 110 piston 132.

After entering the detector 125 the coin will come to rest substantially as referred 120 to in said patent. Thereupon by the turning of the main shaft the cam 121 will engage the cam roll on the lever 129, rocking this lever and, through the link 128, will draw down the operating handle of the 125 detector to test the coin resting in the detector. If the coin is rejected the inherent operation of the detector is such that the detector valve will not move and the coin will drop therefrom into a rejection chute 130

134 through which it passes to the rejected-coin pocket 6 where it can be recovered. On the other hand, if the coin is accepted, then the detector will operate through its own 5 potential energy to swing the valve 127 into a position to drop the coin into a directing chute 136. It will further be explained that the action of the cam 121 occurs approximately during the first half revolution 10 of the main shaft and some time during the remaining half revolution of the shaft the cam will have completed its operation, when the operating handle of the detector will be returned to its initial position 15 by the return of the lever 129 and link 128 which connects with the handle, these parts being returned by the spring-pressed piston 132.

The main shaft 105 during substantially 20 the latter half of its cycle of rotation drives, through a suitable clutch mechanism, a delivery-actuating mechanism, which in turn operates the delivery mechanism proper (not shown) and which may be any one of a variety 25 of kinds.

The delivery-actuating mechanism comprises in the present instance a sleeve 140 mounted to turn on the main shaft. The sleeve carries a driving sprocket 141 the 30 motion of which is communicated to a sprocket 142 on shaft 143 through a sprocket chain 144 and thence to the delivery mechanism proper as such may be. The sleeve 140 bears also a clutch member 146 which 35 is arranged beneath the end of the chute 136, and it consists of a flanged hub of which 147 represents the hub and 148, 149 the respective spaced flanges thereof. These flanges have grooves 150 formed on the inner sides by which a coin dropped from 40 the chute may, when the hub is in a properly turned position, enter the grooves and be maintained in an upright position between the flanges of the hub, the coin then 45 resting upon the hub. The grooves 150 are formed in the flanges on diametrically opposite sides of the clutch member so that a coin dropped from the chute may enter the clutch member at every complete half 50 revolution thereof.

The clutch member carried by the main shaft, and by which the delivery-actuating mechanism is coupled to the main shaft, consists of a bent arm or finger 152 carried 55 by a collar 153 fixed to the shaft. The arm or finger 152 extends up and around one of the flanges of the clutch member 146, the adaptation of the clutch member, in other words, being such that as the main shaft 60 is turned the clutch arm or finger carried by it will engage a coin borne by the clutch member of the delivery-actuating mechanism, and thereby operate this mechanism.

The delivery-actuating mechanism is operated 65 during approximately the last half

revolution of the main shaft and accordingly operates through an arc of 180°. Just before the main shaft has reached the end of its movement the speed of the delivery-actuating mechanism is increased so that this mechanism will travel slightly ahead of the driving shaft and then be stopped in a precisely defined position. This effect is obtained by means of a cam 155 having abruptly and inwardly-inclined edges 70

156. Bearing against this cam is a cam roll 157 carried by a lever 158 pivoted to a bracket 159 fixed to the bed 45 of the machine. Beyond the point of its pivotal connection the lever is provided with an arm 160 against which bears a spring-pressed plunger 161. The spring actuating this plunger is a powerful spring acting not only to hold the roll 157 in continuous contact with the cam, but also sufficiently powerful to turn the cam and the delivery-actuating mechanism with it when the roll enters the depression in the cam and engages either one of the inclined edges 156 thereof. The form of the cam and relative adaptation of the parts is such that the roll will engage either one or the other of the inclined edges 156 of the cam just before the end of the cycle of movement of the driving shaft, thereby causing the cam 90

and delivery-actuating mechanism to travel ahead of the driving shaft and then be stopped by the cam roll seating itself at the lowest point of the depression in the cam. The immediate effect of this auxiliary device for propelling the delivery-actuating mechanism to travel ahead of the main shaft and then bring it to a stop is to release the coin from the pressure exerted by the clutch finger 152, the coin then 100 being free to drop by gravity into any suitable coin receptacle (not shown) for receiving it. The device also acts to stop the delivery-actuating mechanism in just the precise position for the clutch hub of this mechanism to receive another coin at the time of the next operation of the machine. 105

From what has been described it will be seen that it is quite necessary during the cycle of operation of the machine that no 110 coin should be admitted to the operating parts of the machine until it has completed its cycle of operation. Accordingly for such purpose of exclusion the following means is provided: Pivotedly secured to a bracket 115 165 on the side of the coin chute 7 is a lever 166 one arm of which carries a valve 167 which, as the lever is turned, enters through a slot 168 formed in the side of the chute 7 and closes the passage way through the 120 chute, thereby preventing the passage of a coin therethrough. For turning this lever immediately after the passage of a coin through the chute, the other arm of the lever is provided with a bent forked end 169 125 130

which straddles the wire 11 of the trip mechanism, the adaptation of the forked end of the lever being such that as the trip wire is moved downwardly by the coin it will have 5 a drawing engagement with the prong 170 of the lever, thereby turning the same and closing the passage through the chute. The reverse turning of the lever and opening of the passage is effected by movement of the 10 trip wire in a reverse direction during the resetting of the trip mechanism and is effected by the wire drawing against the prong 171 of the lever and thereby moving the valve 167 to an open position and maintaining it in such position, thus clearing the passage through the chute.

The general operation of the machine is as follows: Assuming a coin to be inserted 20 through the coin gage 2 and to have passed by the coin-testing device 3, the coin will then enter the passage through the chute 7. During its passage through the chute 7 the coin will engage the trip lever 8 turning this 25 lever and releasing the drop lever 9. As the trip lever is turned the lever 166 will be turned by it and the valve 167 carried by this lever will close the passageway through the chute to the entrance of another coin. Both the trip lever 8 and the chute-controlling 30 lever 166 will be maintained in their turned positions and the chute closed during the ensuing operation of the machine and until the return of the trip mechanism, which operation is completed, as will later 35 be explained, during the latter part of the machine's cycle of operation.

The fall of the drop hammer 9 starts the machine by releasing latch 74 through action of link 101 and lever 97, the roll 100 on 40 which engages finger 95 to displace the latch and thereby release it from cross-head 67. The plunger 76 is then let go and, actuated by spring 82, it displaces lever 84 which in turn displaces lever 49 carrying contact member 38 between contacts of the leading-in 45 circuit, thereby closing this circuit and starting the motor, which through the connecting mechanism turns the main shaft 105.

The main shaft is turned by the motor 50 through only one complete revolution, and carries with it the various cams 118, 119, 120 and 121. The initial turning of the shaft turns the timing cam 118 by the end of the stop lever 84, which at this time is 55 displaced by the previous operation. As the turning of the shaft continues the reset cam 119 will first engage the cam 70 carried by the cross-head 67 and force back the cross-head against the tension of spring 82 contracting this spring. The cross-head is 60 forced back until the latch 74 drawing over the head of the cross-head, will engage the shoulder 73 therein and hold the cross-head in its retracted and operative position, when 65 the bearing of the reset cam is relieved. The

cross-head when forced back draws with it the plunger 76, the withdrawal of which allows the head of lever 84 to come back and bear tensionally against the peripheral edge of time cam 118 and afterward, just prior 70 to the end of the main shaft's cycle of movement enter a depression in the time cam so that at the end of the complete revolution of the shaft the time cam may engage the top 88 of the lever 84, which accordingly 75 stops the rotation of the main shaft in precisely its initial position. Any jar upon the motor by the sudden stopping of the main shaft is relieved by the slippage of the driving connections between the motor and 80 the shaft as before explained.

During and after the return of lever 84, contact member 38 is held in place between the contacts of the leading-in wire for holding the circuit closed by the engagement of 85 contact-controlling cam 120 with cam roll 54 on lever 49, the bearing of this cam continuing until the end of the main shaft's cycle of movement when the cam allows the lever 49 to return, causing a quick break of 90 the switch connection, thereby stopping the motor.

After the resetting of cross-head 67, the continued movement of the main shaft brings the reset cam 119 to contact with cam roll 95 103 which through arm 102 and connecting spindle, returns lever 97 and thereby through connecting link 101, restores the trip mechanism to its initial position and opens the 100 passage through the chute 7 to the entrance of another coin, this action being completed during the latter half of the main shaft's revolution.

During approximately the first half of the revolution of the main shaft, the coin 105 detector cam 121 will have operated upon lever 129 which through connecting link 129 turns the operating handle of the detector to test the coin resting in the detector, the coin already having entered 110 the detector from the chute 7. If the coin is found unsatisfactory it is delivered through valve 127 of the detector to the rejected coin chute 134, the machine then simply completing its cycle of operation 115 without connecting the driving mechanism with the delivery-actuating mechanism, which under such circumstance remains passive, and no goods are delivered. On the other hand, if the coin is found satisfactory, the operation of the detector is to turn by its own potential energy its valve 127 and thereby control or direct the coin to chute 136, which directs the coin to the clutch mechanism between the driving shaft 125 and the delivery-actuating mechanism, the coin forming the medium by which the clutch engagement is effected, as previously explained.

Inasmuch as the detector is actuated by 130

- the detector cam to test and release a coin during approximately the first half of the revolution of the main shaft, the coin accordingly will be released to form a connecting link between the main shaft and the delivery-actuating mechanism throughout the last half of the shaft's revolution. At some time, also, during the latter half of the main shaft's revolution the detector cam will operate to permit of the restoration of the detector mechanism to its initial position, which effect is obtained by the tensional bearing of the plunger 132 against the lever 129 which connects with the operating arm of the detector. 5
- As the driving shaft approaches the end of its revolution the delivery-actuating mechanism will be advanced by the bearing of the cam roll on the spring-pressed lever 158 against the cam 155, and which not only moves the delivery-actuating mechanism to release the coin from the clutch members, but also acts to stop the delivery-actuating mechanism in precise position for the next 10 operation of the machine.
- The action of the machine is very rapid, all the operations being completed after the insertion of the coin in about two seconds.
- Having thus fully described our invention, we claim and desire to secure by Letters Patent of the United States:—
1. In a coin-controlled vending machine, the combination comprising a delivery-actuating means, a power-operated means for operating said delivery-actuating means, means whereby said power-operated means may be connected to said delivery-actuating means for operating the same under conditions governed by a coin of a determinate character, said last-named means including a coin detector, and means for actuating said coin detector to function by said power-operated means. 15
  2. In a coin-controlled vending machine, the combination comprising a delivery-actuating means, a power-operated means for operating said delivery-actuating means, means controlled by a coin for rendering said power-operated means active, means whereby said power-operated means may be connected to said delivery-actuating means for operating the same only when said coin is one of a determinate character, said last-named means comprising a coin detector, and means whereby said coin detector may be made to function by said power-operated means after said power-operated means has been rendered active by said coin. 20
  3. In a coin-controlled vending machine, the combination comprising a delivery-actuating means, a power-operated means for operating said delivery-actuating means, means controlled by a coin for rendering said power-operated means active, means whereby said power-operated means may be connected to said delivery-actuating means for operating the same only when said coin is one of a determinate character, said last-named means comprising a coin detector, and means whereby said coin detector may be made to function by said power-operated means after said power-operated means has been rendered active by said coin. 25
  4. In a coin-controlled vending machine, the combination comprising a power-operated mechanism, a motor for operating said mechanism, a delivery-actuating mechanism, a coin detector, means whereby a coin may be directed to said detector, means actuated by a coin during the passage thereof to said detector for starting said motor to operate said power-operated mechanism, and means controlled by said detector for controlling the connection of said power operated mechanism and said delivery actuating mechanism under certain conditions determined by said detector. 30
  5. In a coin-controlled vending machine, the combination comprising a power-operated mechanism, a motor for operating said mechanism, a delivery-actuating mechanism, a coin detector, a coin chute leading to said detector, means actuated by a coin during the passage thereof to said detector for starting said motor to operate said power-operated mechanism, means whereby the power-operated mechanism may set said detector for testing a coin, and means controlled by said detector for controlling the connection of said power operating mechanism to said delivery actuating mechanism under conditions determined by said detector. 35
  6. In a coin-controlled vending machine, the combination comprising a power-operated mechanism, a motor for operating said mechanism, a delivery-actuating mechanism, a coin detector, means by which a coin may be directed to said detector, means actuated by a coin during the passage thereof to said detector for starting said motor to operate said power-operated mechanism, means whereby the power-operated mechanism may set said detector for testing the coin, means controlled by said detector for controlling the connection between said power operating mechanism and said delivery actuating mechanism under conditions determined by said detector, means whereby only a determined movement may be imparted to said power-operated mechanism by said motor, and means for stopping the motor. 40
  7. In a coin-controlled vending machine, the combination comprising a power-operated mechanism, a motor for operating said mechanism, a delivery-actuating mechanism, a coin detector, a coin chute leading to the detector, means consisting in part of a trip mechanism actuated by a coin during the passage thereof to said detector for 45

starting said motor to operate said power-operated mechanism, means whereby said trip mechanism may be reset by said power-operated mechanism, means whereby the 5 power-operated mechanism may set said detector for testing a coin, means controlled by said detector for controlling the connection between said power operating mechanism and said delivery actuating mechanism 10 under conditions determined by said detector, means whereby only a determinate movement may be imparted to said power-operated mechanism by said motor, and means whereby the motor may be stopped 15 substantially simultaneously with the stopping of said power-operated mechanism.

8. In a coin-controlled vending machine, the combination comprising a coin chute, a power-operated mechanism, means comprising 20 in part a trip mechanism for controlling the application of power to said power-operated mechanism, said trip mechanism being operable by the passage of a coin through said chute, means for automatically 25 breaking the continuity of said chute after the passage of a coin therethrough and until the resetting of said trip mechanism, and means whereby said trip mechanism may be reset by said power-operated mechanism.

30 9. In a coin-controlled vending machine, the combination comprising a coin chute, a power-operated mechanism, and means for controlling the application of power thereto comprising in part a trip mechanism having 35 a lever operable by a coin gravitating through said chute, a second lever operable from off said first-named lever for breaking the continuity of said chute after the passage of a coin therethrough and until the 40 resetting of said tripping mechanism and means whereby said tripping mechanism may be reset by said power-operated mechanism.

10. In a coin-controlled vending machine, 45 a coin chute having an opening in the side thereof, a lever turned by the passage of a coin through the chute, a second lever having an arm carrying a valve adapted to control the passage through said chute through 50 the opening therein as said second lever is turned, said second lever having also an arm provided with a bent forked end connecting with said first-named lever whereby said second lever may be turned by the turning 55 of said first-named lever.

11. In a coin-controlled vending machine, a coin chute, a power-operated mechanism, a motor for operating said mechanism, means for controlling said motor consisting 60 in part of a trip mechanism actuated by the passage of a coin through said chute, means operated by said trip mechanism for closing said chute after the passage of a coin therethrough for actuating said trip mechanism 65 until the resetting of said trip mechanism,

and means whereby said trip mechanism may be reset during the operation of the machine by said power-operated mechanism.

12. In a coin-controlled vending machine, a power-operated mechanism, means for operating the same, a delivery-actuating mechanism coupled to and operated by the power-operated mechanism under conditions governed by a coin of determinate character, means actuated by a coin whereby the 70 power-operated mechanism may be set in operation, a coin detector for determining by its operation after the setting thereof the character of the coin governing the coupling of the power-operated mechanism to the delivery-actuating mechanism, and means whereby said power-operated mechanism may set said coin detector for testing that coin by which the power-operated mechanism was set in operation.

85 13. In a coin-controlled vending machine, a power-operated mechanism, means for operating the same, a delivery-actuating mechanism coupled to and operated by the power-operated mechanism under conditions governed by a coin of determinate character, means actuated by a coin whereby the power-operated mechanism may be set in operation, a coin detector having a member operated by it under conditions determined by the character of the coin tested by the detector after the setting thereof and the functioning of which member controls the connection between said power-operated mechanism and the delivery-actuating mechanism, and means whereby said power-operated mechanism may set said detector for testing that coin by which the power-operated mechanism was set in operation.

90 14. In a coin-controlled vending machine, the combination comprising a power-applying mechanism, a delivery-actuating mechanism coupled thereto and operated thereby under conditions governed by a coin of determinate character, means controlled by 105 a coin for rendering the power-applying mechanism active, a coin detector for determining by its operation after the setting thereof the character of the coin governing the coupling of the power-applying mechanism to the delivery-actuating mechanism, and means whereby said power-applying mechanism may set said detector for testing that coin by which the power-applying mechanism was rendered active.

110 15. In a coin-controlled vending machine, the combination comprising a power-applying mechanism, a delivery-actuating mechanism, means controlled by a coin for rendering the power-applying mechanism active, means whereby the power-applying mechanism may be coupled to said delivery-actuating mechanism for operating the same under conditions governed by the character of a coin, said last-named means comprising 125 130

in part a coin detector having a member operated by it under conditions governed by the character of the coin tested by said device after the setting thereof and the operation of which member controls the coupling between said power-applying mechanism and said delivery-actuating mechanism, and means whereby said power-applying mechanism may set said testing device for testing that coin by the action of which the power-applying mechanism was rendered active.

16. In a coin-controlled vending machine, the combination comprising a lead for the coin, a motor, a switch controlling the motor, a trip adapted to be operated by a coin during the passage thereof along the lead, means released by said trip whereby said switch may be closed and said motor be rendered operative, means whereby said releasable means may be reset during the operation of the machine, and means whereby said switch may be held closed during the continued operation of the machine.

25 17. In a coin-controlled vending machine, the combination comprising a lead for the coin, a motor, a switch controlling the motor, mechanism operated by the motor, a trip mechanism operable by a coin passing through its lead, mechanism controlled by the trip mechanism and operating to close the switch, means whereby the trip mechanism and mechanism controlled by it may be reset by the motor-driven parts, and means for holding said switch closed during the resetting of said trip mechanism and parts controlled by it.

35 18. In a coin-controlled vending machine, the combination comprising a coin lead, a motor, a switch controlling the motor, a shaft turned by the motor with means for effecting such turning, a trip mechanism operable by a coin passing along its lead, mechanism actuated by the trip mechanism to close said switch and consisting in part of a movable stop, means whereby said trip mechanism and mechanism controlled by it may be reset and said stop released to an engaging position during the operation of said shaft, means for holding the switch closed during the resetting of the trip mechanism and continued operation of the shaft and for releasing the same to open at the end of the cycle of operation of the shaft, and means carried by the shaft to engage said stop for stopping the shaft at the end of its cycle of operation.

45 19. In a coin-controlled vending machine, the combination comprising a lead for the coin, a motor, a switch controlling the motor, a shaft turned by the motor and connections for effecting such turning, a trip mechanism operated by a coin passing along its lead, mechanism actuated by the trip

mechanism to close said switch and comprising a releasable mechanism and a movable stop, a cam carried by the shaft and other connections for resetting said trip mechanism and releasable parts controlled by it and releasing said stop to have an engaging position, a cam carried by the shaft for holding the switch closed during the resetting of said trip mechanism and other parts and for releasing the switch to open at the end of the shaft's cycle of operation, and a cam carried by the shaft for engaging said stop at the end of such cycle of operation.

55 20. In a coin-controlled vending machine, the combination comprising a rotary shaft, a motor and connections for turning said shaft, a switch controlling said motor, a coin detector, a lead by which a coin may be directed to said detector, a trip mechanism operable by a coin passing to said detector, mechanism actuated by the trip mechanism for closing said switch and starting said motor, said trip-controlled mechanism comprising in part a movable stop, means whereby the trip mechanism and certain parts actuated thereby may be reset during the turning of said shaft, means whereby the switch may be held closed during such resetting of the trip mechanism and released to open at the termination of the shaft's cycle of operation, means for setting said detector by the operation of said shaft, a delivery-actuating mechanism, means whereby under conditions predetermined by the detector said delivery-actuating mechanism may be coupled to said shaft after the setting of said detector and operation thereof for testing the coin, and means carried by said shaft for engaging said stop.

65 21. In a coin-controlled vending machine, the combination comprising a shaft, a motor and connections for turning said shaft, a switch controlling the operation of said motor, a coin-controlled actuating mechanism, a releasable stop for said shaft, means operated by said coin-controlled actuating mechanism for releasing said stop and closing said switch, means operable from off said shaft by which said stop-releasing means may be reset and said stop returned to an engaging position during the rotation of said shaft, means operable from off said shaft for holding the switch closed during and after the resetting of the stop-releasing means and for releasing the switch to open at the end of the cycle of operation of the shaft, and means operable from off said shaft to engage said stop for stopping the shaft at the end of its cycle of movement.

75 22. In a coin-controlled vending machine, the combination comprising a rotatable shaft, a motor and connecting means for turning said shaft, a switch controlling the

operation of said motor, means comprising a power-return lever for holding said shaft from turning and in a determinate position, means controlled by a gravity-actuated coin for effecting the release of said holding means and closing of said switch, means whereby said releasing means may be auto-

matically returned to its original position during the resetting of said stop, and means whereby said switch may be automatically held closed for a determinate period after the return of said releasing means. 10
